(57) **CLAIM**

The ornamental design for protective rings for joysticks, as shown and described.

DESCRIPTION

FIG. 1 is a front and top perspective view of protective rings for joysticks showing my new design;

FIG. 2 is a top view thereof;

FIG. 3 is a left view thereof;

FIG. 4 is a right view thereof;

FIG. 5 is a rear view thereof;

FIG. 6 is a front view thereof; and,

FIG. 7 is an exploded view thereof.

The broken lines shown in the drawings, depict environmental structure of the protective rings for joysticks that forms no part of the claim.
